DYNAMOELECTRIC MACHINE

Roger B. Kerr, Jamestown, R. I., assignor to General Electric Company, a corporation of New York

Application February 23, 1954, Serial No. 29,172

Term of patent 14 years

(Cl. D26—5)

Fig. 1.

Fig. 2.

To all whom it may concern:

Be it known that I, Roger B. Kerr, a citizen of the United States, residing at Jamestown, in the county of Newport, State of Rhode Island, have invented a new, original, and ornamental Design for a Dynamoelectric Machine, of which the following is a specification, reference being had to the accompanying drawing, forming a part thereof, in which

Fig. 1 is a perspective view of a dynamoelectric machine embodying the new design; and

Fig. 2 is an end view as seen from the left of Fig. 1.

I claim:

The ornamental design for a dynamoelectric machine, as shown.
